OPTICAL INSTRUMENT

Charles A. Ellis, Southbridge, Mass., assignor to
American Optical Company, Southbridge,
Mass., a voluntary association of Massachusetts

Application October 14, 1949, Serial No. 5,488

Term of patent 14 years

(Cl. D57—1)

To all whom it may concern:

Be it known that I, Charles A. Ellis, a citizen of the United States of America, residing at Southbridge, in the county of Worcester and State of Massachusetts, have invented a new, original, and ornamental Design for an Optical Instrument, of which the following is a specification, reference being made to the accompanying drawings, forming a part thereof.

Fig. 1 is a perspective view of an optical instrument showing my new design; and

Fig. 2 is a side elevational view of the instrument shown in Fig. 1.

The characteristic features of my new design are shown in full lines in the drawing.

I claim:

The ornamental design for an optical instrument, substantially as shown and described.

CHARLES A. ELLIS.
